UNITED STATES PATENT OFFICE.

CHRISTIAN SCHEER, OF TIFFIN, OHIO.

DESIGN FOR A CLOCK-SHELF AND SEWING-CABINET.

SPECIFICATION forming part of Design No. 35,734, dated February 11, 1902.

Application filed January 15, 1902. Serial No. 89,925. Term of patent 3½ years.

To all whom it may concern:

Be it known that I, CHRISTIAN SCHEER, a citizen of the United States, residing at Tiffin, in the county of Seneca and State of Ohio, have invented and produced a new and original Design for a Clock-Shelf and Sewing-Cabinet; and I do hereby declare the following to be a full, clear, and exact description of the invention, such as will enable others skilled in the art to which it appertains to make and use the same.

My invention has reference to a new and original design for a clock-shelf and sewing-cabinet.

15 In the drawings, Figure 1 is a perspective view of my clock-shelf and sewing-cabinet, showing the design thereof. Fig. 2 is a side elevation of the same to further disclose the design.

20 As shown in the drawings, the essential feature of my design comprises a substantially rectangular top 1, the side brackets 2, the back 3, having its lower portion cut to

form a scroll, the substantially square drawer-section 4, the upholstered sections 5 on either 25 side of the section 4, arranged below the top, and the cross-piece 6, secured between the back and the side brackets and provided on its top with a series of upwardly-extending spool-spindles 7 and on its bottom 30 with a series of hooks 8. The upholstered sections 5 are provided with ornamental marginal beads 9.

Having described my new and original design, what I claim, and desire to secure by 35 Letters Patent, is—

The design for a clock-shelf and sewing-cabinet, substantially as herein shown and described.

In testimony whereof I hereunto affix my 40 signature in presence of two witnesses.

CHRISTIAN SCHEER.
